UNITED STATES PATENT OFFICE.

GEORGE M. RICHARDS, OF NEW BRUNSWICK, NEW JERSEY.

HYDROCARBON-ENGINE.

SPECIFICATION forming part of Letters Patent No. 399,348, dated March 12, 1889.

Application filed March 31, 1888. Serial No. 269,190. (No model.)

To all whom it may concern:

Be it known that I, GEORGE M. RICHARDS, a citizen of the United States, residing at New Brunswick, in the county of Middlesex and State of New Jersey, have invented certain new and useful Improvements in Hydrocarbon-Engines; of which the following is a specification.

My invention relates to motor-engines deriving their power from the combustion of liquid hydrocarbons or other combustible liquids which are vaporized and mixed with air in order to form a combustible mixture or vapor. It is also in part applicable to engines for burning mixtures of gas and air.

The objects of my invention are to produce an engine for generating power by the consumption of cheap liquid fuel—such as crude petroleum—which shall be economical in its operation, convenient and easy to manage, portable, shall develop high efficiency, and shall yield large power in proportion to its weight.

Prior to this invention engines of various forms have been devised for generating power by the combustion of hydrocarbon liquids—such as petroleum—vaporized and mixed with air to form a highly-combustible mixture. In such engines the liquid combustible is introduced in measured quantities into contact with a jet or stream of compressed air in such manner that the liquid is sprayed or atomized and forced through heated diaphragms in order to vaporize it, after which the vaporous mixture is ignited, and in its combustion expands many times in volume, and thereby generates a considerable pressure, which is utilized to drive a piston forward in a power-cylinder, and through the piston to give motion to a crank. On the return-stroke of the piston the gaseous products of combustion are expelled from the cylinder through an escape or exhaust valve, and upon each successive power-stroke of the piston a fresh charge of mixed air and vapor is admitted to the cylinder through an inlet or admission valve and, being ignited, expands and forces forward the piston. The ignition of the combustible charge is effected in various ways—as by a master-light brought into communication at proper intervals with the combustible charge, or by the passage of electric sparks at the proper instant, or by the continuous inflow to the power-cylinder during both the power and exhaust strokes of a sufficient jet of combustible vapor to maintain a flame. The latter method is considered the preferable one. Oil-engines of this character include as essential parts a power-cylinder with its piston, the power-shaft with its cranks and fly-wheel, the pump or compressor for compressing air, and a pump for injecting the oil. In addition valves are necessary for determining the admission of air to the power-cylinder and the exhaust of the spent gaseous products therefrom. The exhaust-valve is opened mechanically during the entire or nearly the entire return-stroke of the power-piston. The admission-valve should be operated with a varying cut-off, determined by means of a governor, in order to graduate the quantity of air supplied proportionally to the work being done by the engine. The stroke of the oil-pump may also advantageously be varied in like manner in order to inject more or less oil as the work of the engine increases or diminishes. It is also customary to provide engines of this class with a cylinder or reservoir for holding compressed air in order that during the operation of the engine a supply of air may be pumped into this reservoir and there confined by the closing of a valve in order to be held in readiness for use when it next is required to start the engine, and before the engine has acquired sufficient momentum and energy to be able to pump the air for its use under the requisite pressure.

Hydrocarbon - engines as heretofore constructed have been subject to certain defects, which have prevented their extended introduction. They have been liable to stop unexpectedly and without apparent cause while in use. They have been subject to explosions, which at times have been so severe as to disable them, and which, if less severe, have had the effect of making the motion of the engine irregular. They have been difficult to start, requiring great skill and expertness to effect their proper starting, and liable to be started with so little momentum as to stop before a second or third stroke could be made, thereby wasting the supply of compressed air and re-

quiring to have a new supply pumped up by hand before the engine could be finally started. They have been subject to considerable difficulty in the lubrication of the power-cylinder, and in other respects the construction of such engines has been defective and unsatisfactory in use, so that they have required close attention to keep them running properly and have been liable to break down or wear out prematurely.

My present invention aims to correct the defects to which such engines have heretofore been subject. It is especially directed to securing a thorough subdivision and vaporization of the hydrocarbon liquid, to insuring the retention of the flame, so that the engine shall not be stopped by the extinguishment thereof, to providing improved means for insuring the correct and easy starting of the engine, and in general to improving the details of construction thereof.

My improved engine in its simplest form includes a power-cylinder and piston, a crank-shaft, a pump-cylinder and piston or other air-compressor, an oil-injecting pump, an exhaust-valve for the power-cylinder, and an admission-valve therefor, with suitable valve-gear for operating these valves. The power-cylinder and piston are single-acting and may be duplicated or triplicated in order to provide a continuous forward impulse, if such be desired. If a single cylinder is employed a heavy fly-wheel is used to store up momentum and effect the return-stroke of the piston. Both the power and pump cylinders are water-jacketed, as usual, an improved construction being employed to insure a thorough circulation of the water through their jackets in order that they shall be cooled uniformly and continuously.

The machine is provided with a governor, as usual, to determine the cut-off of the air-admission valve. According to the preferred construction, the valve-gear is operated by cams on an auxiliary cam-shaft driven by gearing from the power-shaft and at the same speed, and this shaft also operates the oil-injecting pump. The power-cylinder is provided with air-inlet and vaporizing chambers of improved construction, whereby the vaporization of the oil is made more complete, and whereby the extinguishment of the flame is more effectually guarded against than in previous engines. A lighting-hole is provided communicating with the vapor-chamber for igniting the combustible vapors in order to start the engine, this hole being provided with a valve or gate for closing it, as heretofore, and means being also provided, as heretofore, for retaining the admission-valve temporarily closed during the starting of the engine. In starting it is necessary, after lighting the vapor, to first close the lighting-hole and then instantly throw open the admission-valve, and if the latter operation is not performed with the requisite quickness the engine will stop before completing one revolution. As here-

tofore constructed, it has been necessary for the operator to become very adept in performing this manipulation in order to insure the correct starting of the engine.

My improved engine is provided with automatic means for throwing open the admission-valve instantly upon the closing of the lighting-hole, so that no skill on the part of the operator is demanded.

My improved engine may be constructed in various ways in order to adapt it for different uses, it being understood that the arrangement and construction of its parts may undergo such variations as engine designs are commonly subjected to.

The accompanying drawings show one construction by means of which my invention may be carried into practice, the particular engine here illustrated being a single-acting engine with but one power-cylinder, adapted for use as a stationary engine or for driving yachts or launches, the cylinders being arranged vertically with the crank-shaft beneath them.

In the accompanying drawings, Figure 1 is an elevation of the left-hand end of my improved engine, partly in vertical section, in the plane of the line 1 1 in Fig. 2. Fig. 2 is a vertical mid-section thereof, looking from the front and cut on the line 2 2 in Fig. 1. Fig. 3 is a plan thereof. Fig. 4 is a horizontal section cut in the plane of the lines 4 4 in Figs. 1 and 2. Fig. 5 is a vertical mid-section of the pump-cylinder, looking from the right hand end of the machine, cut in the plane of the line 5 5 in Fig. 2, the pump-plunger being shown in elevation. Fig. 6 is an elevation of the power-cylinder, looking from the right, with the upper portion thereof in section in the plane of the axis of the exhaust-valve, and showing a fragment of the parts in section, as indicated by the line 6 6 in Fig. 2. Fig. 7 is a fragmentary transverse section of the power-cylinder on a larger scale, looking from the left, the section being cut through the axis of the cylinder and through the axis of the inlet-valve. Fig. 8 is an inverted plan of the inlet-valve chamber cut in the plane of the line 8 8 in Fig. 7. Fig. 9 is an elevation looking from the rear, showing the top of the power-cylinder with the inlet-valve gear, the latter being partly in section on the line 9 9 in Figs. 3 and 7. Fig. 10 is a plan, partly in horizontal section, of a portion of the mechanism shown in Fig. 9. Fig. 11 is an enlargement of a portion of Fig. 7, showing the inlet-valves open. Fig. 12 is an elevation answering to Fig. 9 and showing a modified construction.

In order that the construction of my improved machine may be well understood, I will proceed to describe in detail the particular construction thereof shown in Figs. 1 to 10 of the drawings.

Let A designate the main frame of the machine; B, the power-cylinder; C, the pump-cylinder; D, the power-shaft; E, the fly-wheel

mounted thereon; F and G, cranks in said shaft, and H and H' storage-tanks for compressed air.

K is the power-piston in the cylinder B, 5 and M the pump piston or plunger in the cylinder C.

P in Figs. 1 and 3 is the oil-injecting pump, and T is the auxiliary cam-shaft or counter-shaft for driving the valve-gear.

10 The frame A is constructed in the form of a hollow base or shell inclosing the lower working parts, and the cylinders B and C are mounted on it in vertical position. These cylinders are water-jacketed, as usual in machines of this class. The storage-tanks H and H' are arranged within the lower part of the shell or casing A.

The main shaft D is hung in bearings a a 15 at opposite ends of the casing A, as shown in Fig. 2, and its middle portion is re-enforced by resting on pillows b b, supported on the cross-frame e, Fig. 1, the ends of which are bolted to lugs c', Figs. 1 and 2, formed on the inside of the shell A. The wrist of the crank 20 F passes through a rotary bearing in a block, d, which slides in a transverse slot, d', in a cross-head, I, fixed to the lower end of the piston-rod J, the upper end of which is fixed to the power-piston K, which works in the power- 25 cylinder D. The front and rear ends of the cross-head I are guided by working between the opposite guideways or bearing-surfaces e e, formed on the interior of the outer shell, A. In lieu of this sliding block and cross-head a 30 pitman directly engaging the crank-wrist may be employed, being well known as an equivalent thereof.

The crank G connects by a pitman, L, with the pump-plunger M, which works in the 35 pump-cylinder C. The upper end, l, of this pitman is spherical, and is seated in a hemispherical socket in the pump-plunger, a ring, l', being fastened to the under side of the plunger and embracing the spherical end l 40 closely enough to prevent its being pulled out of its socket. This construction constitutes a ball-and-socket connection between the plunger and the pitman L, whereby the latter is free to oscillate and the pump-plunger is free to rotate independently thereof.

The pump-cylinder C is provided at its top 45 with an air-inlet valve, N, and an outlet-valve, O, as shown in Fig. 5. The inlet-valve opens inwardly to the cylinder from an air-chamber, f', into which opens an air-passage, f, which 50 leads from the space within the shell A upwardly through the jacket surrounding the pump-cylinder to the chamber f', so that by the operation of the pump air is drawn up 55 through this passage and enters the pump-cylinder through the valve N during the downstroke of the plunger M, and on being compressed by the upstroke of the plunger it escapes by lifting the outlet-valve O, which 60 is a check-valve opening outwardly, being pressed to its seat by a spring, o'. The air on escaping through this valve passes into an

air-chest, g', from which leads the pipe i, controlled by the throttle-valve P', as shown in Fig. 4. From the air-chest g' three pipes, g g, 70 extend downward, as shown in Figs. 4 and 5, through the water-jacket around the pump-cylinder C, and terminate in a pocket, g², as shown in Figs. 5 and 1, formed in the shell A. The outline of this pocket is shown in 75 dotted lines in Fig. 4. From this pocket a pipe, h, Fig. 1, extends down and opens into the compressed-air reservoir H, and a branch pipe, h', leads from the pipe h and opens into the compressed-air reservoir H', this latter 80 being provided with a valve or stop-cock, h², operated from the rear of the engine by a hand-wheel, h³. The compressed-air reservoir H acts as an air-cushion for holding during the operation of the engine a small reserve of 85 air, and the reservoir H' serves as a storage-reservoir to hold a supply of compressed air to be employed for starting the engine after it has been stopped, the compressed air being confined therein by the closing of the valve h². 90

Referring to Figs. 3 and 4, the air-pipe i leads from the outlet or compressed-air chest of the pump across the front of the engine to the pump-cylinder, where it communicates with the passage i', formed in the shell or jacket at the top thereof, as shown in Figs. 4 and 7. This passage i' extends upward and opens into the air-chamber q in the valve-chest Q, as shown in Fig. 7.

The power-cylinder is provided with admission and exhaust valves R and S, as shown in Figs. 2 and 4. The admission-valve R opens from the air-chamber q, as shown in Figs. 2 and 7, into a shallow commingling-chamber, V, from which a supplemental valve, R', opens 100 into a vapor chamber or passage, W. These parts are best shown in Fig. 7. Beneath the vapor-chamber W is the usual intercepting diaphragm, U, constructed, preferably, of one or more layers of fine wire-gauze confined between perforated plates u u above and below. Beneath the diaphragm U is an igniting-chamber, W', for the vaporized fluid, and this chamber has free communication with the upper end of the power-cylinder B through 105 an opening, j. A lighting port or passage, k, communicates with the chamber W' and extends thence to the outer air at the top of the cylinder, as shown in Fig. 2, being provided with a valve or gate, K', for closing it. 110

From the oil-pump P a pipe, p, extends to the valve-chest Q and terminates in a nozzle, p', Figs. 7 and 8, which enters the latter and passes across the air-passage i', opening into the shallow commingling-chamber V at one 115 side thereof. At the opposite side of this chamber is an air-inlet tube, q', which projects up into the chamber q and has a small perforation adapted to admit the passage of a minute stream of compressed air from the 120 chamber q into the chamber V when the valve R is closed. In the bottom of the chest Q, which is preferably one casting, as shown, is formed a deep annular groove, m, exterior to

and inclosing the chamber W, as best shown in Figs. 7 and 8. This annular groove communicates with the chamber V by means of a series of small holes, $m' m'$, as shown in Figs. 5 7 and 8. The groove m is closed by the perforated plate u of the diaphragm U, so that it forms an annular chamber, which chamber is filled or packed with some absorbent material capable of holding a quantity of oil and sufficiently porous to admit the passage of air through it. A thick felt answers the purpose well; but many other materials are admissible. The bottom or floor of the chamber V is made very slightly conical, so that it shelves or slopes away from the valve-opening in its center and toward the holes m' near its periphery. Thus when the valve R' is closed the oil which enters through the nozzle p' is caused to flow around the chamber V and to pass down the perforations m' into the groove or annular chamber m , thereby saturating the absorbent filling in the latter. At the same time a small stream of compressed air enters the chamber V through the nozzle q' , and, distributing itself in the chamber, passes down through the perforations $m' m'$ and blows down through the saturated absorbent filling in the groove m . Thus the air absorbs some of the oil with which this filling is saturated and carries it through the diaphragm U, which during the operation of the engine is highly heated, so that the vapor in passing through it is raised to a high temperature, and the mixture of air and hydrocarbon vapor thus entering the chamber W' through the diaphragm is ignited by the flame already existing in the chamber W' and burns, thereby maintaining the flame therein during the period that the valves R 40 R' are closed. The products of combustion from the flame thus maintained flow out from the chamber W' through the opening j into the cylinder B, from which they escape through the exhaust-valve S, Figs. 2 and 6, 45 into the exhaust-chamber s and up the exhaust-pipe s', through which they are led into a chimney or flue and thence to the outer air.

The inlet-valve R, which when seated closes communication for the air from the chamber q to the commingling-chamber V, (except through the jet-pipe q' , as already stated,) is in the construction shown a tappet-valve pressed to its seat by a spring, r , Fig. 7, and having a stem, n , passing out through a stuffing-box in the top of the valve-chest Q, as shown, through which stem the valve is lifted. The supplemental valve, R', which when seated closes communication between the chamber V and the chamber or passage 55 W, is also in the construction shown a tappet-valve, being pressed to its seat by a spring, r' , and having a stem, n' , by which to lift it. In the construction shown, which is the preferred construction, the lower portion of the stem n is made tubular and the stem n' projects up into it, and the spring r' , which is of lighter tension than the spring r , presses up-

ward against the under side of the main inlet-valve R.

It is necessary that the valve R shall be first 70 lifted to admit air from the chamber q into the chamber V before the valve R' is lifted to admit the air or vapor into the chamber W. This is best accomplished by the construction shown, wherein the valve R' is connected to the valve R through the medium of a slotted connection or articulation, or by any other connection admitting a certain amount of lost motion, so that when power is applied to the valve R to lift it it 80 will lift to the extent of this lost motion before the valve R' will be lifted. In closing, the valve R' will close first; but this is merely incidental to the articulated connection. In the particular construction shown this connection is made by means of a slot in the stem n' entered by a pin passed diametrically across through the prolonged lower end of the stem n ; but any other suitable construction 85 may be adopted.

The operation may now be understood in so far as the power-piston and the inlet and exhaust valves of the power-cylinder are concerned.

I will assume that the engine has been 95 started and is already running under full speed. At each stroke a measured quantity of oil is injected from the pump P through the pipe p and nozzle p' into the commingling-chamber V. During the exhaust or upstroke 100 of the power-piston the inlet-valves R R' are closed and the exhaust-valve S is open. During this time a small flame is maintained in the chamber W' (which may be called the "ignition-chamber") by means of a reduced 105 stream of air admitted through the nozzle q' , perforations m' , grooves m , and heated diaphragms U, as already described. At the end of the upstroke of the piston the exhaust-valve S is closed by the valve-gear; or, in case 110 it is desired to cushion the piston, the exhaust-valve may be closed shortly before the end of the stroke. Before (or immediately after) the piston commences its downstroke, and preferably shortly before it completes its 115 upstroke, the valve-stem n is lifted, thereby lifting the valve R and admitting compressed air from the chamber q into the commingling-chamber V, and instantly thereafter, by the continued lift of the stem n , the valve R' is 120 lifted, thereby admitting air and vapor into the chamber or passage W. During the instant after the lifting of the valve R and before the lifting of the valve R' a rush of air occurs from the chamber q into the commingling-chamber V, into which latter chamber a charge of oil has already been injected, and this oil is thus driven by the air down the perforations $m' m'$ and into the absorbent filling in the groove m . The air, having for 125 an instant no other means of escape, forces its way through this absorbent filling, taking up the oil with which the latter is saturated and flowing with the oil which it thus ab-

sorbs through the diaphragm U, which imparts heat to the vapor. Instantly thereafter the valve R' opens and admits a large volume of air from the commingling-chamber V into the chamber or passage W, the air thus admitted carrying with it a considerable part of the oil from the chamber V, which oil is carried with the air down through the diaphragm U, and is thereby vaporized and emerges into the ignition-chamber W' along with the vapor formed by the flow of oil and air through the saturated absorbent in the groove m. Thus a considerable volume of air and hydrocarbon vapor or gas is rapidly admitted into the chamber W', whereupon it is ignited by the flame therein and its combustion is effected, so that it expands many times in volume, and, flowing through the opening j into the cylinder B, it exerts a considerable pressure therein against the piston K and forces the latter on its downstroke. The admission of air and hydrocarbon vapor or gas continues as long as the inlet-valves remain open—a duration which, if a cut-off-valve gear is employed, will vary from time to time, according to the work which the engine is performing.

With the construction of engine shown it is intended that the valves shall be closed at the latest at five-eighths of the stroke, the remaining three-eighths of the stroke being effected by the expansion of the burning gases. During the power-stroke the combustion of the hydrocarbon vapor or gas is not confined to the ignition-chamber W, but extends into the cylinder B. The action is not an explosive one, the power being generated entirely by the expansion of the gases during their combustion, which takes place slowly as compared with an explosive expansion, and is continuous as long as mixed air and vapor is admitted through the valves and diaphragms. When the piston reaches the end of its power-stroke, the exhaust-valve S is opened, thereby relieving the pressure in the cylinder, and during the return-stroke the piston forces the consumed gases or products of combustion out of the cylinder, wiping the latter clean and preparing it for the next power-stroke. As soon as the inlet-valves are closed, thereby arresting the large volume of inflowing air and vapor to the cylinder, the flame which may have been expelled by the draft of inflowing gases from the chamber W' into the cylinder will burn back into the ignition-chamber and will be there maintained by the small inflow of air through the nozzle q', as first described.

The lift of the supplemental valve R' is not sufficient to cause it to obstruct the inflow of air through the seat of the valve R. It is to be understood, however, that the valve R' when lifted will stand in the way of the direct flow of compressed air from the chamber q into the chamber W and will deflect the air and cause it to circulate or reverberate in the chamber V, creating an outward or radial current at the top thereof and an in-

ward or centripetal current at the bottom thereof, flowing toward the seat of the valve R'. These currents are shown by the arrows 70 in Fig. 11, where the valves are shown fully lifted. By means of this circulation the compressed air, which, in consequence of its compression, is highly heated, and consequently very absorbent of vapor, is caused to take up 75 considerable of the oil, which is spread in a film over the lower surface or floor of the chamber V, and to carry the vapor thus absorbed with it into the chamber W and through the diaphragm. The lift of the valve 80 R' is sufficient to cause by far the greater portion of the air which enters the chamber V to pass down through its seat into the chamber W, so that perhaps nine-tenths or more of the air passes thus directly through the 85 diaphragm, and the small remaining portion passes through the absorbent filling in the chamber or groove m. The injection of oil into the chamber V continues for about half the revolution of the main crank-shaft, so 90 that if it commences shortly before the up-stroke of the piston is completed it will continue during nearly or quite the time that the inlet-valves remain open on the down-stroke. Thus during the entire time that the 95 valve R' is lifted and the circulation of compressed air in the chamber V continues the film of oil on the floor of this chamber is replenished by the continued injection of oil, so that all the air flowing into the cylinder 100 while the valve R' is lifted is enriched by absorbing hydrocarbon vapor. The slight coning of the bottom of the chamber V, so that it inclines upward toward the seat of the valve R', causes the oil to flow around the 105 circumference of the chamber and spread itself over the floor thereof, instead of flowing mainly in one stream toward the valve-seat, as it would otherwise tend to do.

The principal object of the supplemental 110 valve R' is to cause the entire flow of compressed air to be directed for a portion of each stroke through the absorbent filling in the annular chamber m. This results in forcing the oil which has been injected into the 115 chamber V to flow down the perforations m' into this chamber m in order to saturate the absorbent filling therein. In this manner a charge of oil is stored up at each stroke to enrich the small jet of air which flows through 120 the nozzle q' and chamber m to maintain the flame during the return-stroke of the piston. This construction insures that the air admitted during this stroke shall carry with it sufficient oil for this purpose, so that the flame 125 is maintained with certainty and the stoppage of the engine due to extinguishment of this flame is avoided.

Oil-engines made prior to my invention have had an air-chamber corresponding to the 130 chamber q in my engine, an air-inlet valve answering to my valve R, a passage from this valve to the intercepting-diaphragm answering to the passage or chamber W in my en-

gine, and an igniting-chamber corresponding to my chamber W' beyond the diaphragm. The oil has been injected into an annular groove or chamber filled with absorbent material and answering to the chamber m in my engine; but the air, instead of passing partly through the absorbent filling in this chamber, has been brought in contact with the oil only by being caused to flow in a choked stream across the end of the annular chamber, and consequently in contact with the absorbent filling. Such a construction is shown in the patent to G. B. Brayton, No. 151,468, dated June 2, 1874. Engines thus constructed have proved defective in that the oil has not been sufficiently vaporized and absorbed by the air and in that the small stream of air admitted to maintain the flame during the exhaust-stroke was not sufficiently enriched by absorption of oil to enable it certainly to maintain ignition within the cylinder, so that the engine was both inefficient or uneconomical in its generation of power from the fuel consumed and liable to frequent stoppages.

Oil-engines have also been made wherein the oil, instead of being injected directly into an annular chamber or groove—such as m —was injected into a chamber somewhat similar to the chamber V in my engine, and from which it flowed through perforations into the filling in the chamber m ; but in that engine there was no valve separating the chamber V from the chamber W , and the only means of forcing the oil into the absorbent filling was by deflecting a portion of the stream of air entering the cylinder during the power-stroke by means of an obstruction by which the area of the opening from the chamber V to the chamber W was reduced. The construction of my engine constitutes an important practical improvement on that of the engine just referred to, since for an instant during each stroke the entire pressure of the air is caused to act to force a charge of oil into the absorbent filling. In the engine referred to also there was no means for causing the circulation of air in the chamber corresponding in position to my chamber V , and the bottom of this chamber was not sloped upwardly toward the outlet-opening therefrom, so that there was no such action as occurs in the chamber V of my present engine—namely, the passage of a current of heated compressed air over a film of oil on its way to the power-cylinder during the power-stroke.

According to my present invention I place in the bottom of the ignition-chamber W' a washer-shaped plate, u' , of wrought-iron or other suitable material, which plate is kept heated red-hot by the flame in the chamber W' and acts as a further means of preventing the extinguishment of the flame or to cause its instant relighting in case it should become extinguished. This plate has a hole through its center corresponding in position to the opening j and either of the same size or slightly smaller, as shown, or even a little

larger, and the plate is preferably so arranged as to stand a little above the bottom of the chamber.

70

The inlet and exhaust valves of the power-cylinder may be operated by any suitable valve-gear. The gear for this purpose shown in the drawings possesses no especial novelty, being of a construction commonly used in gas and other engines, and it may be replaced by any other suitable gearing that may be preferred as being better suited for any particular type of engine. The lift of the valves is controlled by cams on a shaft, T , which is driven from the main shaft D and at the same speed through the medium of gears $e' e^2 e^3$. The inlet-valves $R R'$ are lifted by means of a cam, R^2 , on this shaft, Fig. 7, the movement being transmitted to the valve-stem n through an elbow-lever, t , connecting-rod t' , and rock-lever t'' , the latter having its forward end forked to straddle the stem n , and taking under a head, n'' , fixed on the latter and adjustable up or down thereon, in order to determine the precise lift to be given to the valves R and R' .

85

The elbow-lever t has a roller, t^3 , mounted on one arm, which roller comes in contact with the cam R^2 . This cam R^2 is mounted on a sleeve which can slide longitudinally on the shaft T in order to bring different portions of the cam against the roller t^3 , and thereby determine the cut-off of the inlet-valves, in the manner common in engines of this class. The longitudinal movement of the cam is determined by the governor T' , (shown in Figs. 2 and 3,) which is of ordinary construction, and from which longitudinal movement is imparted to the cam in the well-known manner.

95

The exhaust-valve S is operated from the shaft T by the mechanism shown in Fig. 6. It is closed by a spring, s'' , and opened forcibly by a cam, S' , on the shaft T , the movement of this cam being transmitted to the stem of the valve through the medium of a rod, j' , having a cross-head or foot, j^2 , fixed on its lower end to receive the thrust of the cam, and connected at its upper end to a rock-lever, j^3 , the forward arm of which is jointed to the valve-stem.

100

The inlet-valve N of the air-pump C is closed by a spring, o' , and opened forcibly by a cam, N' , on the shaft T , the movement of which is transmitted to the valve-stem through a lever, v , carrying a roller, v' , against the cam, and jointed at its end to a rod, v^2 , which connects to the rear arm of a rock-lever, v^3 , the forward arm of which is jointed to the valve-stem, all as shown in Fig. 5.

115

The oil-pump P , the suction-pipe p'' of which leads from a suitable receptacle containing a supply of oil, is operated from the shaft T by means of an eccentric, a' , Fig. 3, through a rod, a'' , and its valves are worked by an eccentric, b' , through a rod, b'' , in the usual manner. The eccentrics a' and b' are, as usual, connected to the shaft T through the

120

125

medium of a ratchet, (not shown,) so that they are turned forward by the shaft, but may be themselves turned forward without rotating the shaft. This is necessary in starting the engine in order to pump a charge of oil into the chamber V before the first stroke. For this purpose a crank, T'', is provided, which is fixed to the eccentrics a' b'.

I will now describe the means for starting the engine. The lighting hole or port k is formed entirely in the cylinder-head and opens upwardly to the top thereof, and a sliding valve or gate, K', is provided to close it. This gate K' is carried by a horizontally-swinging lever, K'', through the medium of an adjusting-screw, k'', by means of which any desired downward pressure may be given to the gate to enable it to resist the upward pressure of the gases through the lighting-port, this strain being resisted by the lever, which is fulcrumed on a stud close to its connection with the gate. In Figs. 3 and 10 the lever is shown in full lines in the position it occupies when the gate is closed over the lighting-port, and the dotted lines in Fig. 3 and full lines in Fig. 9 show the lever swung out so as to open wide the lighting-port. In thus swinging out the lever the gate K' slides on an arc-shaped bearing-surface, k', which is carried out by a bracket beyond the cylinder-head.

In starting the engine it is necessary that the air-inlet valve R shall be kept closed while the lighting-port k is open, as otherwise there would be so strong an outflow of vapor through the lighting-hole as to blow the flame outside and prevent its burning back into the ignition-chamber. The current due to the flow of air through the nozzle q' is sufficient for the purpose of ignition and is so reduced that the outflow through the lighting-port is slow, and consequently the flame is enabled to burn down into the chamber W'. It is essential, however, that the inlet-valve shall be opened wide instantly after the closing of the lighting-port, in order to give a powerful impetus to the power-piston, in order that the engine may acquire sufficient momentum to carry the crank around for its first revolution. It will be understood that, in starting, the engine is set with its crank just beyond the upper center, and that the engine will commence to move as soon as the vapor is lighted and the lighting-port is closed. If, then, the opening of the inlet-valves is delayed beyond a very brief interval, there will not be sufficient vapor admitted to the power-cylinder to force the piston downward with energy enough to carry the crank back on its upstroke and open the valves for the second downstroke of the piston. In oil-engines prior to my invention means have been provided for holding the air-inlet valve closed while the lighting-port was open; but such means have been operated by hand and without any connection with the means for closing the lighting-port. Hence in starting the engine it was necessary to first close the lighting-port by one-hand ma-

nipulation and then throw open the inlet-valve by another, and great skill and experience were necessary in order to perform this second manipulation with the requisite rapidity and properly timed to the first. The result of an unskillful or unsuccessful manipulation was the stopping of the engine before one revolution was completed, with the loss of the stored-up compressed air which had been used in starting it.

My invention, by the device which I will now proceed to describe, provides for the correct successive manipulations of the lighting-port gate and the air-inlet valve by automatic means and without the necessity for any skill on the part of the operator.

The rock-lever t'', through which the inlet-valves are opened, is fulcrumed on an axis 85 which is adjustable up and down, as heretofore, in order that by lowering its axis the valves may be held closed, notwithstanding the effort of the valve-gear to open them. In the construction shown the lever t'' is fulcrumed to an upright forked standard, A', Figs. 7 and 9, which slides up or down in a fixed tubular socket, A'', and the lower end of which rests on a sliding wedge or cam-bar, B', as shown in Fig. 9. When this wedge is pulled out, the standard A' is lowered, so that the valve-gear is impotent to lift the valves. This is the position of the parts while lighting the vapors.

The sliding wedge or cam B' is constructed to be operated by means of the lever K'', which manipulates the gate K'. To this end the lever is provided with a lateral arm, w, which is hooked and engages a hook, w', which is connected to the wedge B' through the medium of a flat or leaf spring, w''. Normally the parts are engaged as shown in Fig. 10; but upon throwing the lever K'' to the right its hooked arm w encounters the hook w', and thereby pulls out the wedge B' until the latter is arrested by a stop-pin, c'', Fig. 9, whereupon the spring w'' yields and frees the hook w' from the arm w, so that the lever K'' can be thrown around as far as may be desired in order to open wide the lighting-port. The wedge B' is thus pulled out and the valve R consequently closed before the lighting-port is opened. After lighting the vapor which issues from the lighting-port, the lever K'' is thrown forcibly back to the position shown in Fig. 10, whereupon the arm w displaces and passes the hook w' while the gate K' is closing, and its end encounters an abrupt face, w³, on the wedge B', whereby it drives or pushes the wedge back to its normal position, thereby lifting the standard A', and consequently lifting the valves R R', (that is, if the valve-gear is, as it should be, in the position in which these valves would be lifted or partially lifted in the normal operation of the engine.) The proportions of the parts are such that the lighting-port is closed before the valves R R' are opened; but the latter operation occurs necessarily instantly after the

former. It will be obvious that the mechanical connections or expedients by means of which this result is attained may be variously modified without materially affecting the operation. The distinctive feature of this part of my invention is that the manipulation of a single lever or equivalent element—such as the lever K'' —shall effect first the closing of the lighting-port and instantly thereafter shall restore the valve-gear to its normal condition, so that if the cam R^2 is in the proper position for opening the inlet-valve the latter will by this movement be opened. This novel feature in oil-engines having been disclosed by me and one method of carrying it into practice having been fully shown and described in my present application, it will be easy for any intelligent mechanic or engine-designer to devise or construct other mechanisms for accomplishing the purpose according to the essential principle of my invention. As an example of one modification that may be adopted, I have shown the construction illustrated in Fig. 12, where the lever t'' is fulcrumed to a vertically-sliding block, A' , capable of sliding in vertical ways in a fixed standard, A'' , and raised or lowered by a toggle-arm, B'' , pivoted at its upper end to the block A' and carrying at its lower end a roller, which rolls on the flat surface of the cylinder-head. The arm B'' is connected by means of a jointed link, D' , to the gate K' for closing the lighting-port k or to the lever K'' for operating this gate. As the gate is opened the link D' pulls the arm B'' from its normal vertical position, so that it lets the block A' descend, thereby dropping the fulcrum of the lever t'' and closing the valve R . When the gate K' is moved back to close the lighting-port, the arm B'' is pushed back to the vertical position, thereby again lifting the block A' and throwing the valve R open. It will be observed that in both the constructions shown the movement for opening and closing the inlet-valves is communicated from the lever K'' to the fulcrum of the rocking lever t'' . This, however, is not essential, as the action by which the valve R is closed and opened may take place at any point in the connecting mechanism between the cam R^2 and the valve.

The operation of starting my improved engine is as follows: First turn the crank until it is just beyond its up-center; then throw out the hand-lever K'' to close the valves R R' and open the lighting-port; then turn the crank T'' about five or six revolutions, so that the pump P shall inject a surplus of oil; then by means of the hand-wheel P'' open the throttle-valve P' in the air-pipe h , thereby admitting air from the compressed-air reservoir H' to flow into the air-chamber q , whereupon a small stream of air will be admitted through the nozzle q' , and, passing through the chamber m , it will vaporize some oil and flow out through the lighting-port; then light the vapor at this port; then close or partially close

the throttle-valve in order to reduce the pressure and enable the flame to burn back through the lighting-port into the ignition-chamber; then open the throttle-valve wide and immediately thereafter throw back the lever K'' , thereby closing the lighting-port and opening the valves R R' , whereupon the engine starts. These operations are simple in themselves, are easily learned, and require no especial skill or dexterity to perform them.

The cylinders B and C are water-jacketed, as usual, the water entering through a pipe, x , Fig. 2, into the bottom of the pump-cylinder jacket X , flowing upward to the top thereof, flowing back downward through a tube, x' , which stands vertically in the jacket on the opposite side, is open at its upper end, which is close to the top of the jacket, and communicates at its bottom end with a passage, x^2 , formed in the cast base or shell A . This passage leads to the left in Fig. 2 and extends upwardly, communicating with a passage, x^3 , formed in the casting of the power-cylinder B and leading into the water-jacket X' thereof at the bottom. The water flows upward in this jacket to the top thereof, whence it flows through a vertical tube, x^4 , which projects upwardly within the jacket and opens close to the top thereof, and the lower end of which communicates with a passage, x^5 , formed in the cylinder-casting, from which a water-outlet tube, x^6 , carries the heated water away. The circulation of water is caused by connecting the pipe x with the city water-works or other source of water. The use of the tubes x' and x^4 insures the thorough circulation of the water from end to end of the jackets and affords a very simple and cheap construction for that purpose.

The lubrication of the power-piston in its cylinder has always been a matter of difficulty in engines of this class on account of the heating of the interior of the power-cylinder by the combustion of the vapors therein and the condensation of carbonaceous products on the walls thereof. My invention provides an improved means of lubrication applicable to upright cylinders. The piston, in addition to being formed with ring-packings around it of any suitable or well-known construction, is prolonged downwardly around its periphery somewhat after the manner of bucket plungers, the annular prolongation being tapered or beveled to an edge, as shown at y in Fig. 2. Just beneath the lower open end of the power-cylinder is placed an oil-basin, y' , which is filled or partially filled with lubricating-oil, the level of the latter being such that at the extreme downstroke of the piston its beveled edge y shall dip into the oil for a short distance, sufficient to become moistened or smeared with the oil, so that upon its upstroke it shall carry up a small quantity of oil with it and spread this oil upon the interior surface of the power-cylinder. In the upstroke of the piston the oil which has adhered to the beveled edge y runs down to the

extreme edge thereof and is thereby transferred to the surface of the cylinder. The beveling of the downward prolongation y has a twofold purpose, serving not only to direct the oil as it thus runs down toward the surface of the cylinder, but also acting as it dips into the bath of oil beneath at the extreme downstroke of the piston to part the oil easily, so that it enters it without splashing the oil and creating unnecessary commotion and waste of oil. I also provide novel means for lubricating the plunger M of the air pump or compressor and the ball-and-socket joint l of its pitman L . An oil-cup, Y , Fig. 2, is arranged exterior to the cylinder C , and from it an oil-discharge pipe or nozzle, Y' , leads through the water-jacket and opens into the cylinder against the plunger. The plunger is provided with two sets of ring-packings, z and z' , which are spaced apart a distance preferably equal, or nearly so, to the stroke of the plunger. The oil-inlet Y' is arranged, preferably, about midway between the two packings when the plunger is at midstroke, as shown, so that during the movement of the plunger it communicates always with the space between the two sets of packing-rings and discharges oil into this space whence the oil is distributed over the surface of the cylinder. The lubrication of the ball-and-socket joint l is effected by an oil-passage, z^2 , which leads from any convenient point between the packing-rings z and z' and conducts the oil thence to the ball-socket. Preferably this passage leads from the socket of the lower ring-packing, z' , as shown in Fig. 2. The pressure of the compressed air in the pump-cylinder, leaking to some extent past the upper ring-packing, drives some of the oil from the space between the packings through the passage z^2 to lubricate the ball-and-socket joint.

The lubrication of the wrists of the cranks F and G is effected by the construction clearly shown in Fig. 2 with reference to the crank F . This crank is formed on the side next the bearing a with a disk, F' , having on its face next the bearing an undercut concentric groove, f^2 , from which an oil-duct, f^3 , leads radially outward to the center of the crank-wrist and extends thence into the latter and to the exterior thereof, as clearly shown. Oil which is introduced into the groove f^2 , either by working over from the bearing a or by the insertion of an oil-can nozzle into it, is during the operation of the engine carried by centrifugal force through the oil-duct f^3 out to the surface of the crank-wrist. The lubrication of the crank G is precisely the same as that of the crank F .

In Fig. 1, Z is a pressure-gage which communicates by a pipe, q'' , with the air-pocket g^2 , and serves to show the degree of pressure of the compressed air. In the normal operation of the engine the air is compressed to from sixty to one hundred pounds per square inch, although, of course, the pressure may

vary according to the design and proportions of the engine. It will be understood that the working-pressure of the burning vapor in the power-cylinder must not be as great as that of the compressed air, as if it were the compressed air would not flow into the power-cylinder during the power-stroke. The power developed by the engine is due to the differential action of the two pistons, that in the power-cylinder having a mechanical advantage over that in the pump-cylinder. In the particular engine shown this mechanical advantage is due partly to the area of the piston K being slightly in excess of that of the plunger M and partly to the power-crank F being of much greater throw than the pump-crank G , their relative throw being shown as two to one.

The tubes g , through which the compressed air passes on its way to the cylinders H H' , extend through the water-jacket X , which surrounds the pump-cylinder. This construction causes the hot compressed air in passing down through these tubes to give up a considerable portion of its heat to the water, so that it is cooled before it reaches the cylinders.

It is not essential to my invention that the air compressor or pump shall be constructed as a part of the engine, since it may be an entirely distinct machine. In fact, any source whatever of compressed air may be used.

Throughout this specification and the claims I have referred to "oil" as the fuel or combustible to be employed for driving the engine. It is to be understood, however, that any combustible liquid that can be vaporized or sprayed and mixed with air to form a combustible mixture may be substituted for oil and will be the equivalent thereof. Gaseous hydrocarbons may also be employed in place of oil or liquid fuel.

I make no claim in this application to the means for lubricating the power-piston, consisting of the flange y , dipping into the oil-vessel y' , as I have made this feature the subject of another application for patent for improvements in piston-lubricators for motor-engines, filed October 31, 1888, Serial No. 289,606, a division of the present application, and I specifically reserve this matter to be claimed in that application. I also disclaim herein the improvement relating to the air-compressor, the same consisting of the lubrication of the plunger M by means of the packing-rings z and z' , spaced wide apart, with the oil-duct Y' communicating with the space between them, and also the water-jacketed tubes g , through which the compressed air passes on its way to the reservoir H , since these features are reserved to be claimed in my divisional application for patent for improvements in air-compressors, filed October 31, 1888, Serial No. 239,661.

I claim as my invention in motor-engines consuming liquid hydrocarbon fuel, or other analogous engines, the following-defined novel

features and combinations, substantially as hereinbefore specified, namely:

1. In a motor-engine, the combination, with the power-cylinder and its piston, its inlet and exhaust valves, a source of compressed air, and a compressed-air passage leading thence to the power-cylinder and controlled by the inlet-valve, of an oil-commingling chamber communicating with said passage, having its bottom or floor formed with a slight upward incline toward the outlet to the cylinder and arranged to be traversed by the air flowing toward said outlet, a source of oil, and an oil-duct leading to said commingling-chamber.
2. In a motor-engine, the combination, with the power-cylinder and its piston, its inlet and exhaust valves, a source of compressed air, and an air-passage leading thence to the power-cylinder and controlled by the inlet-valve, of an oil-commingling chamber arranged to be traversed by the compressed air in its passage, having its bottom or floor formed with an upward incline toward the outlet of the cylinder and provided with a deflector for causing the air to circulate in said chamber, a source of oil, and an oil-duct leading to said chamber.
3. In a motor-engine, the combination, with the power-cylinder and its piston, its inlet and exhaust valves, a source of compressed air, and an air-passage leading thence to the power-cylinder and controlled by the inlet-valve, of an oil-commingling chamber entered by said air-passage at its top and having an outlet through its bottom to the cylinder, a valve for closing said outlet, adapted when lifted to act as a deflector for causing the air to circulate outwardly and inwardly in said chamber, a source of oil, and an oil-duct leading to said chamber.
4. In a motor-engine, the combination, with the power-cylinder and its piston, a source of compressed air, and an air passage leading thence to the power-cylinder, of a commingling-chamber communicating with said passage, a valve controlling the admission of compressed air into said chamber, a valve controlling the outlet from said chamber to the cylinder, a source of oil, and an oil-duct leading to said commingling-chamber, whereby the oil in said chamber is vaporized by the circulation of air therethrough and controlled by said valves.
5. In a motor-engine, the combination, with the power-cylinder and its piston, its inlet and exhaust valves, a source of compressed air and an air-passage leading thence to the power-cylinder and controlled by the inlet-valve, a source of oil communicating with said air-passage, whereby the air may absorb oil on its way to the cylinder, and an oil chamber or groove having an absorbent filling and communicating with said source of oil, of a restricted air-inlet duct extending from said air-passage through said oil-chamber to the power-cylinder, adapted to admit a reduced flow of air through said absorbent

filling while the inlet-valve is closed, whereby the injection of combustible vapor into the cylinder during the exhaust-stroke is insured for the maintenance of ignition therein.

6. In a motor-engine, the combination, with the power-cylinder and its piston, its inlet and exhaust valves, a source of compressed air and an air-passage leading thence to the power-cylinder and controlled by the inlet-valve, and a source of oil communicating with said air-passage, whereby the air may absorb oil on its way to the cylinder, of an oil chamber or groove having an absorbent filling, an air-passage through said oil-chamber to the cylinder, and a valve and valve-gear constructed to admit a momentary charge of compressed air into said oil-chamber at intervals in order to drive the oil into and through the absorbent filling therein.

7. The combination, with the power-cylinder and its piston, its inlet and exhaust valves, a source of compressed air and an air-passage leading thence to the cylinder, and a source of oil communicating with said air-passage, whereby the air may absorb oil on its way to the cylinder, of an oil chamber or groove having an absorbent filling, an air and oil chamber communicating with said oil-chamber through perforations, and into which the oil is injected, a valve for admitting air from said air-passage into said oil and air chamber, an air-passage through said oil-chamber to the cylinder, and a valve-gear constructed to open said valve momentarily at intervals in order to admit a charge of compressed air into said oil and air chamber and cause the same to drive the oil through said perforations into said oil-chamber and into and through the absorbent filling therein.

8. The combination, with the power-cylinder and its piston, its inlet and exhaust valves, a source of compressed air and an air-passage leading thence to the power-cylinder, and a source of oil communicating with said air-passage, whereby the air may absorb oil on its way to the cylinder, of an oil chamber or groove having an absorbent filling and communicating with the cylinder, an air and oil chamber into which oil is injected and which communicates with said oil-chamber through perforations, a restricted air-inlet extending from said air-passage into said air and oil chamber, adapted to admit a reduced flow of air through said absorbent filling and into the cylinder to maintain ignition therein during the exhaust-stroke, a valve for admitting air from said air-passage into said air and oil chamber, and a valve-gear constructed to open said valve momentarily at intervals in order to admit a charge of compressed air into said air and oil chamber and cause the same to drive the oil through said perforations into said oil-chamber and into and through the absorbent filling therein.

9. The combination, with the power-cylinder and its piston, a source of compressed air and an air-passage leading thence to the power-

- cylinder, a commingling-chamber traversed by said air-passage, an oil chamber or groove having an absorbent filling communicating with the power-cylinder and communicating through perforations with said commingling-chamber, a source of oil discharging into said commingling-chamber, and a restricted air-inlet from said air-passage into said commingling-chamber, adapted to admit a reduced flow of air through said absorbent filling and into the cylinder to maintain ignition during the exhaust-stroke, of a main and supplemental air-inlet valve, the one adapted to control the flow of compressed air into said commingling-chamber and the other to control its flow from said commingling-chamber to the cylinder, and a valve-gear constructed to open said main inlet-valve at each stroke in advance of said auxiliary valve and thereby to admit a momentary charge of compressed air into said commingling-chamber to drive the oil through said perforations into said oil-chamber and into and through the absorbent filling therein.
10. The combination, with the power-cylinder and its piston, a source of compressed air and an air-passage leading thence to the power-cylinder, a commingling-chamber traversed by said air-passage, an oil chamber or groove having an absorbent filling and communicating with said commingling-chamber and the cylinder, a source of oil discharging into said commingling-chamber, and a restricted air-inlet from said air-passage into said commingling-chamber, of a main air-inlet valve adapted to control the flow of compressed air into said commingling-chamber and having a valve-stem, a valve-gear constructed to move said stem to open and close said valve, and a supplemental valve adapted to control the flow of air from said commingling-chamber to the cylinder and connected to said main valve by a mechanical connection providing some lost motion, whereby the main valve opens before and closes after the supplemental valve.
11. The combination, with the power-cylinder and its piston, its inlet and exhaust valves, a passage for compressed air controlled by the inlet-valve, and an ignition-chamber between the inlet-valve and said cylinder and communicating with the latter through a contracted opening, of a plate or diaphragm in said ignition-chamber adjacent to the outlet thereof from adapted to be heated by the flame therein and to aid in maintaining ignition.
12. In a motor-engine operating by the combustion of hydrocarbon vapor in its power-cylinder, the combination, with the power-cylinder, its inlet and exhaust valves, a valve-gear for operating them, a device connected with said valve-gear for rendering the latter impotent to open said inlet-valve, a lighting-port communicating with the power-cylinder and opening to the exterior thereof, and a gate or valve for closing said port, of a handle connected with and adapted to close said gate, and a connection between said handle and said device for rendering impotent the valve-gear, operating substantially as described, to render the valve-gear operative and open the inlet-valve by the act of closing said lighting-port gate, whereby the starting of the engine is rendered automatic.
13. In a motor-engine operating by the combustion of hydrocarbon vapor in its power-cylinder, the combination, with the power-cylinder, its inlet and exhaust valves, a valve-gear for operating them, a valve-closing device connected with said valve-gear for holding the inlet-valve temporarily closed during the igniting of the vapor to start the engine, a lighting-port communicating with the power-cylinder and opening to the exterior thereof, and a gate or valve for closing said port, of a handle connected with and adapted to open and close said gate, and a mechanical connection between said handle and said valve-closing device adapted when moved to close said gate to simultaneously throw said valve-closing device out of operation and thereby open the inlet-valve by the act of closing the lighting-port.
14. In a motor-engine operating by the combustion of hydrocarbon vapor in its power-cylinder, the combination, with the power-cylinder, its inlet and exhaust valves, a source of compressed air and an air-passage leading thence to the power-cylinder, a lighting-port communicating with the power-cylinder and opening to the exterior thereof, a gate or valve for closing said port, and a valve-closing device adapted to close temporarily a valve controlling the passage of compressed air or vapor into the power-cylinder, of a handle for closing said lighting-port gate, and a connection between said handle and said valve-closing device adapted to transmit to the latter the movement of the handle when closing said gate, and thereby to throw said device out of action and consequently to effect the admission of compressed air or vapor to the cylinder, whereby such admission is effected automatically by the act of closing the lighting-port.
15. In a motor-engine, the combination, with the power-cylinder, its inlet and exhaust valves, a valve-gear for operating them, a valve-closing device connected with said valve-gear for holding the inlet-valve temporarily closed during the igniting of the vapor to start the engine, a lighting-port communicating with the power-cylinder and opening to the exterior thereof, and a gate or valve for closing said port, of a handle connected with and adapted to open and close said gate, and also connected with and adapted to operate said valve-closing device, the said connections being arranged, on the movement of said handle in one direction, to first throw said valve-closing device into action to close the valve and subsequently open the lighting-port gate, and on the movement of the handle in the opposite direction to first close

the lighting-port and subsequently open the inlet-valve.

16. In a motor-engine, the combination, with the power-cylinder, its inlet and exhaust valves, and a valve-gear for operating them, comprising a lever through which movement is communicated to the inlet-valve, a valve-closing device engaging the fulcrum of said lever and constructed, when actuated, to move said fulcrum and thereby close the valve, whereby the valve-gear is rendered impotent to open said valve, a lighting-port communicating with the power-cylinder and opening to the exterior, and a gate for closing said port, of a handle connected with and adapted to operate said gate, and also connected with and adapted to operate said valve-closing device, whereby the opening or closing of the lighting-port and the closing or opening of the inlet-valve are effected by a single stroke of said handle.

17. The combination, with the power-cylinder, its lighting-port, its inlet-valve, and a valve-gear for operating said valve, comprising a rock-lever, a movable standard to which said rock-lever is fulcrumed, a sliding wedge or cam engaging said standard and adapted by its movement to raise or lower the latter and thereby to open or close the inlet-valve, and a gate for closing said lighting-port, of a hand-lever for operating said gate arranged to encounter said wedge in its movement of closing said gate and thereby drive in said wedge and throw open the inlet-valve.

18. The combination, with the power-cylinder, 35 its lighting-port, a gate for closing said port, the inlet-valve, and a valve-gear for operating said valve, comprising a rock-lever, t'' , of an adjustable standard, A' , for moving the fulcrum of said lever, a wedge, B' , acting on 40 said standard, a hand-lever, K'' , for opening and closing said gate, and means for engaging said lever with and disengaging it from said wedge, consisting of a hooked arm, w , on the one part, a shoulder, w^3 , and a spring-mounted hook, w' , on the other part, operating substantially as described.

19. In a motor-engine operating by the combustion of hydrocarbon vapor, the combination, with a cylinder constructed with a water 50 space or jacket in its walls and water inlet and outlet passages communicating with said jacket at one end of the cylinder, of a tube within said jacket leading from one of said passages and extending through the jacket 55 and opening at or near the opposite end thereof, whereby a circulation of water from end to end of the jacket is assured.

In witness whereof I have hereunto signed my name in the presence of two subscribing 60 witnesses.
